By his Attorney Almanzo

UNITED STATES PATENT OFFICE.

ALBERT E. TEPFER, OF NEW YORK, N. Y.

DESIGN FOR A BEAM-LIGHT.

48,840.

Specification for Design.

Patented Apr. 4, 1916.

Application filed December 15, 1915. Serial No. 67,064. Term of patent 7 years.

To all whom it may concern:

Be it known that I, ALBERT E. TEPFER, a citizen of the United States, residing at New York city, in the county and State of New York, have invented a new, original, and ornamental Design for a Beam-Light, of which the following is a specification; reference being had to the accompanying drawing, forming part thereof.

Figure 1 is a side elevational view of

a beam light showing my new design; and Fig. 2 is a plan view thereof.

I claim:—

The ornamental design for a beam light, as shown.

ALBERT E. TEPFER.

Witnesses:

CLARICE FRANCK,

JUDITH PARDEE.
